UNITED STATES PATENT OFFICE.

JAMES PAULL AND ALBERT A. MILLER, OF WELLSBURG, WEST VIRGINIA, ASSIGNEES
TO THE EAGLE MANUFACTURING COMPANY, OF WELLSBURG, WEST VIRGINIA, A CORPORATION OF WEST VIRGINIA.

DESIGN FOR A CANDY CONTAINER.

Application filed January 13, 1928 Serial No. 24,866. Term of patent 3½ years.

To all whom it may concern:

Be it known that we, JAMES PAULL and ALBERT A. MILLER, citizens of the United States, residing at Wellsburg, in the county of Brooke and State of West Virginia, have invented a new, original, and ornamental Design for Candy Containers, of which the following is a specification, reference being had to the accompanying drawing, forming part thereof.

The figure is a perspective view of a candy container, illustrating the design.

We claim:

The ornamental design for a candy container, as shown.

JAMES PAULL.
ALBERT A. MILLER.
